UNITED STATES PATENT OFFICE.

CHARLES B. SMITH, OF NEW YORK, N. Y.

ELECTRICAL SIGNALING OR CALLING SYSTEM.

SPECIFICATION forming part of Letters Patent No. 727,704, dated May 12, 1903.

Application filed March 8, 1900. Renewed October 22, 1902. Serial No. 128,251. (No model.)

To all whom it may concern:

Be it known that I, CHARLES B. SMITH, a citizen of the United States, residing at New York city, borough of Manhattan, State of New York, have invented certain new and useful Improvements in Electrical Signaling or Calling Systems, of which the following is a specification.

The object of my invention is to provide a signaling or calling system wherein a comparatively large number of signaling or indicating instruments can be operated over a relatively small number of lines or circuits; and in carrying out my invention I provide a conductor with one or more relays adapted to control the circuits of relays that are connected with different conductors, and the last-named relays are adapted to control the circuits of signaling instruments associated with different selector-lines, whereby when the circuit of the first-mentioned conductor is established its relay or relays will establish the circuit of the second-named relays, and thereupon current thrown on the conductor connected with the appropriate relay will cause that relay to close the circuits of the corresponding signaling instruments, and when current is thrown on the selector-line to which the desired signaling instrument is connected said instrument only will be operated. I have shown my improved system as provided with a central office, from which the various conductors and lines lead, and suitable circuit-controlling devices are provided at central, whereby current can be thrown on the different lines and conductors to enable the circuit for the desired signaling instrument to be readily established and said instrument operated.

I may enlarge the capacity of the selector-lines without unduly increasing their number by utilizing two or more of the first-mentioned conductors, each provided with a relay or relays to control relays that are adapted to establish the circuits of additional signaling instruments associated with the said selector-lines, as will be more fully explained hereinafter.

The invention also consists in the novel details of improvement that will be more fully hereinafter set forth and then pointed out in the claims.

In the accompanying drawing, which is a

diagrammatic view of a signaling or calling system embodying my invention, a central office is indicated at A, at which suitable circuit-controlling and current-transmitting devices are located, and from the central office a conductor 1 leads, as to ground, for a suitable number of subscribers or substations, which for convenience I denominate as arranged in groups or sets, as B C D, each group or set containing a suitable number of substations, as b b' b² in group B, c c' c² in group C, and d d' d² in group D. Connected to line 1 are one or more relays 2, adapted to control the circuits of a plurality of relays 3, there being one or more of such relays 3 for each group or set of stations, as B C D, which relays are adapted to control the circuits of signaling or indicating instruments, as 4, at the substations. The circuit for the relay or relays 3 of each group or set of stations, as B C D, while being controlled by the relay or relays of conductor 1, is to be established over a different conductor leading from central, as 5 6 7. I have shown normally open spurs or branches 3^a for the relay or relays 3 of each group of stations, connected to a different conductor 5 6 7, the contacts of each spur or branch being controlled by the relay or relays of conductor 1. The relays 3 of the groups of stations B C D control the circuits of the signaling instruments of the substations in such groups, and each substation of a group of stations is associated with a selector-line, as 8, 9, or 10, arranged for all the stations, a signaling instrument in each group of stations being associated with the same selector-line—that is to say, the stations b c d of groups B C D are associated with line 8, the stations b' c' d' of said groups are associated with line 9, and the stations b² c² d² of the same groups are associated with line 10. I have shown spurs or branches leading from the lines 8 9 10 to the corresponding signaling or indicating instrument 4, the contacts of which spurs or branches are controlled by the relays 3.

From the foregoing it will be understood that if it is desired to signal to a station that is associated with conductor 1 current will be thrown on that conductor, whereupon its relay or relays 2 will establish the circuits of the relays 3 associated with the corresponding groups of stations B C D, and current will

also be thrown on the conductor 5, 6, or 7 associated with the group of stations embracing the desired station, whereupon such relay or relays 3 will close the circuits of the 5 substations within such group. For instance, if a station in a group B is to be called current will be thrown first on conductor 1 and then on conductor 5, and the relay or relays 3 of that group will establish the circuits of the 10 signaling instruments at stations $b b' b^2$. The circuits of the signaling instruments of substations in a group of stations having been thus established, current will be thrown on the line 8, 9, or 10 connected with the signaling instrument of the station desired. For instance, if station b is to be called current will be thrown on line 8, and thus the signaling instrument 4 at that station will operate, but the signaling instruments at stations $b' b^2$ will not operate, and likewise if station b' or b^2 were to be called current would be thrown on line 9 or 10. If a station in any other group of stations were to be called, as C or D, current would be thrown 20 on conductor 6 or 7 instead of 5 to operate the relay of spur or branch 3^a of group C or D to establish the circuits of the signaling instruments in such group, and thereupon current will be thrown on line 8, 9, or 10 of 25 the desired station in such group.

I have for convenience of illustration shown three stations in a group and three groups of stations, all associated with conductor 1, there being three lines 8 9 10 for the 30 three stations in a group. It will be understood, however, that the number of stations in a group can be increased as much as desired, in which event there will be a selector-line, as 8 9 10, for each station in a group, 35 and it will also be understood that there may be as many groups of stations as desired. Where the number of groups of stations associated with conductor 1 are increased, the number of conductors, as 5 6 7, with their relays 3, will be correspondingly increased—that is to say, there will be one such conductor for each group of stations associated with conductor 1. In such cases the relay or relays of conductor 1 will control the circuits of the 40 relay or relays 3 of each group of stations, which in turn control the circuits of the signaling instruments of the stations in such groups. If there are five stations in a group and three groups of stations, I would employ 45 five selector-lines, three conductors, as 5 6 7, and one conductor, as 1, making nine lines and conductors for fifteen stations. Likewise if there were five stations in a group and five groups of stations I would use five 50 selector-lines, five conductors, as 5 6 7, and one conductor, as 1, making eleven lines for twenty-five stations. The number of stations in a group and the number of groups of stations may only be limited by the convenience 55 of establishing the line.

I can increase the capacity of the system by increasing the number of relay-conductors,

as 1, and providing groups of stations for such conductors. For instance, I may provide a conductor 1^b, having one or more relays 2^a 70 and groups of stations E F G associated therewith, and a conductor 1^c, having one or more relays 2^b and groups of stations H I J associated therewith, each station in such groups having a signaling or indicating instrument 75 associated with the selector-lines 8 9 10, as described with respect to the groups of stations B C D, the circuits of the signaling instruments of each of such groups being controlled by relays 3 associated with conductors 5 6 7, 80 as previously described, which relays 3 are controlled by the relays 2^a 2^b in manner described with respect to the relays 2 of conductor 1. In the arrangement shown there are three main relay-conductors 1 1^b 1^c, and 85 there are three groups of stations associated with each of such conductors and three stations in each group. It will be readily understood that with five selector-lines five relay-conductors, as 5 6 7, and five main conductors, as 1 1^b 1^c, one hundred and twenty-five stations can be accommodated, or fifteen lines and conductors. It will thus be seen that I may employ conductors or lines arranged in sets, as 1 1^b 1^c and 5 6 7 and 8 9 10, 90 there being one or more electrically-operating devices associated with each conductor or line, and that thus the devices of one set of lines control the circuits of the devices of another set, which in turn control the circuits of a 100 different set, and thereby the circuit of a desired instrument, as 4, can be established.

Instead of using a plurality of relays on either or all of the conductors 1 1^b 1^c I may use a single relay that is adapted to operate 105 the contacts of the spur-lines 3^a of the corresponding groups of stations, as shown in connection with line 1^c. The contacts connected with the spurs 3^a are shown insulated from each other, but all operated from the one relay; but the effect is the same as if a different relay were used for each spur 3^a. Likewise instead of using a plurality of relays for the spur or branch lines 3^a I may use a single relay on either or all of such branches, adapted 110 to operate the contacts of the circuits of the signaling instruments of the corresponding group of stations, the contacts of the respective signaling-instrument circuits being insulated from each other, as shown in connection 115 with the group of stations J; but whether one or more relays are used on such conductors or branches is immaterial to the successful operation of my invention, provided a conductor, as 1 1^b 1^c, has the proper relay or relays and contacts to control the spurs or branches 3^a of a plurality of groups of stations, and provided also that the relay or relays on the spurs or branches 3^a of a group or groups of stations operate contacts to establish 120 the circuits of the signaling instruments of the corresponding stations in a group, it being understood that the number of relays employed in such relations will be in accord-

ance with the convenience in establishing the circuits and the proximity of different stations or groups of stations to each other.

Any suitable means may be provided for throwing the appropriate current on the lines and conductors. I have shown an arrangement at central A whereby by a simple manipulation of a switch or push-button current can be thrown on all the lines and conductors necessary to establish connection with and operate the signaling instrument at the desired station. I have shown one of such switches or push-buttons for each station, and they are arranged in groups or sets with reference to the conductors 5 6 7 in accordance with the number of stations in a group, as those stations are associated with said conductors. Such switches are also associated with the conductors 1, 1^b, or 1^c whose relay controls such groups of stations, and each switch is likewise associated with the selector-line 8, 9, or 10 that is connected with the signaling instrument corresponding to the switch. The arrangement I have shown for the purpose may be described as follows: 11 12 13 14 15 16 17 18 19 are switches or push-buttons corresponding to the stations associated with line 1, each switch corresponding to a station in the groups of stations B C D. The group 30 of switches 11 12 13, that correspond to the stations in group B, have contacts 11^a 12^a 13^a, connected with conductor 5, the group of switches 14 15 16, corresponding to the stations in group C, have similar contacts connected with conductor 6, and the group of switches 17 18 19, corresponding to group D, have contacts connected with conductor 7. These switches also have contacts 11^b 12^b, &c., connected with conductor 1, and the switches 11 12 13, corresponding to group B, have contacts 11^c 12^c 13^c, connected with selector-lines 8 9 10, respectively. The switches 14 15 16 of group C also have similar contacts, connected, respectively, with selector-lines 8 9 10, and switches 17 18 19 of group D likewise have corresponding contacts, connected, respectively, with said lines. Each of these switches has contacts which may be denominated generally as 20 21, the contacts 50 20 being adapted to connect with the contacts of selector-lines 8 9 10 and the contacts 21 being adapted to connect with the contacts connected with conductor 1 and conductors 5 6 7. As the groups of switches associated with lines 1^b and 1^c have contacts and connections with the other lines and conductors similar to those above described, it will not be necessary to further explain them, as they will be clearly understood from the drawing, it being noticed, however, that there is a push-button or switch connected with each conductor 1, 1^b, or 1^c for each station of the different groups of stations associated with such conductors. For convenience I have shown the contacts 60 20 of the selector-lines 8 9 10 as connected with a conductor 22, with which is associated a generator 23 in well-known manner, and the

contacts 21 are connected with a conductor 24, with which is connected a battery 25, and whereby a single generator and battery is 70 adapted to provide current for the various lines; but of course the connections for throwing current upon the lines may be otherwise arranged, if desired.

Suppose it is desired to call a station in group B, as station b. Switch 11 will be operated, whereupon the circuits of the generator and battery will be closed and current will flow from battery 25 through contacts 21 and 11^b to conductor 1, and thence to ground, operating the relay or relays 2, which will close the circuits of the spurs or branches 3^a of the groups of stations B C D, and thereupon current will flow from battery 25 by contact 11^a to conductor 5, and thence to ground, operating the relay or relays 3 of the group of stations B only, and thus the other groups of stations whose spur-lines 3^a were operated by the relay or relays on conductor 1 have no current on their lines. The relays 3 of group 90 B will thus establish the circuits of the signaling instruments of all the stations in that group, and thereupon current will flow from generator 23 through contacts 20 and 11^c over line 8 and will only find ground at station B, 95 thereupon operating the signaling instrument 4 thereat. No other signaling instrument associated with line 8 will operate, because the circuits thereof that are controlled by conductors 5 6 7 have not been operated. If a station 100 in group C or D were desired, the corresponding switch would be operated and current would be thrown on line 6 or 7 to operate the relays 3 of the desired group of stations, and then current would flow over line 8 9 10, according to which switch had been operated, to operate the desired signaling instrument. Likewise, if a station in a group on conductor 1^b or 1^c were desired the corresponding push-button or switch in the appropriate group of switches 110 would be operated, and current from battery 25 and generator 23 would operate the relays and signaling instrument in the manner hereinbefore outlined with respect to line 1.

I do not limit my invention to the particular arrangement indicated and described, as the same may be varied without departing from the spirit thereof.

Having now described my invention, what I claim is—

1. A signaling system comprising a conductor having a relay or relays, a plurality of conductors having relays whose circuits are controlled by the relay or relays of the first-mentioned conductor, a plurality of signaling instruments whose circuits are controlled by the relays of said plurality of conductors, and a plurality of selector-lines associated with said signaling instruments.

2. A signaling system comprising a conductor having one or more relays, a plurality of conductors to each of which one or more relays are connected, the circuits for the last-named conductors and their relays being con-

- trolled by the relay or relays of the first-mentioned conductor, a plurality of signaling instruments whose circuits are controlled by the relays of the plurality of conductors, and 5 a plurality of selector-lines associated with said signaling instruments, a signaling instrument of each selector-line being associated with the relay or relays of a conductor of the plurality of conductors.
- 10 3. A signaling system comprising a conductor having one or more relays, a plurality of conductors to each of which a spur or branch is connected and adapted to be controlled by said relay or relays, said spurs or branches 15 each having one or more relays, a plurality of selector-lines and signaling instruments associated therewith, the circuits of said signaling instruments being controlled by the relays of the corresponding spurs or branches.
- 20 4. A signaling system comprising a conductor having one or more relays, a plurality of conductors to each of which a spur or branch is connected and adapted to be controlled by said relay or relays, said spurs or branches 25 each having one or more relays, a plurality of selector-lines and signaling instruments, a group of signaling instruments associated with said selector-lines being associated with each conductor of said plurality of conductors.
- 30 5. A signaling system comprising a conductor having one or more relays, a plurality of stations arranged in groups, each station having a signaling instrument, a conductor for 35 each group of stations, whose circuit is controlled by a relay of the first-mentioned conductor, a plurality of selector-lines, each selector-line being associated with a station in each group, each of said conductors of a group 40 of stations having a relay or relays adapted to control the circuits of the signaling instruments of the corresponding group of stations.
- 45 6. The combination of a plurality of relay-conductors, a plurality of stations arranged in groups associated with said conductors, a plurality of conductors each associated with groups of stations, said plurality of conductors each having one or more relays for the corresponding group of stations, the circuits of 50 such relays being controlled by the relays of the first-mentioned conductors, a signaling instrument in each station, the circuits of
- said instruments being controlled by the relays of said plurality of conductors, and a plurality of selector-conductors associated 55 with said signaling instruments.
7. The combination of a plurality of conductors each having one or more relays, a plurality of stations arranged in groups there being a plurality of groups of stations for each 60 of said conductors, a plurality of conductors 5, 6, 7, corresponding to the number of groups of stations connected with either of the first-mentioned conductors, said plurality of conductors each having one or more relays for 65 the corresponding group of stations, the circuit of the relay or relays of each of such conductors being controlled by the relay or relays of the corresponding first-mentioned conductor, a signaling instrument in each station, a plurality of selector-conductors associated 70 with signaling instruments in groups of stations, the circuits of the signaling instruments of each group of stations being controlled by the relay or relays of the corresponding conductor, 75 5, 6, or 7.
8. The combination of a plurality of selector-lines, a plurality of conductors having relays to control the circuits of said selector-lines, and a conductor having a relay or relays to control the circuits of said plurality of conductors, with a plurality of switches associated with the last-mentioned conductor, groups of said switches being associated with each conductor of said plurality of conductors, and a switch of each group being associated 85 with a selector-line.
9. The combination of a plurality of selector-lines, a plurality of conductors having relays to control the circuits of said selector-lines, and a set of conductors having relays to control the circuits of said plurality of conductors, with a plurality of switches, groups of which are associated with each conductor of said set of conductors, groups of switches 90 that are associated with each conductor of a set being associated with the same conductor of said plurality of conductors, and a switch in each of the last-named groups being associated with a selector-line.
